US00D900777S

(12) United States Design Patent (10) Patent No.: US D900,777 S
(45) Date of Patent: * Nov. 3, 2020

(54) MOBILE PHONE

(71) Applicant: LG Electronics Inc., Seoul (KR)

(72) Inventors: Hyoni Kim, Seoul (KR); Byeongwook Kim, Seoul (KR); Jiyoun Cha, Seoul (KR); Hyunggon Ryu, Seoul (KR); Seungbeom Park, Seoul (KR)

(73) Assignee: LG ELECTRONICS INC., Seoul (KR)

() Term: 15 Years

(21) Appl. No.: 35/506,846

(22) Filed: Nov. 23, 2018

(80) Hague Agreement Data

Int. Filing Date: Nov. 23, 2018

Int. Reg. No.: DM/200379

Int. Reg. Date: Nov. 23, 2018

Int. Reg. Pub. Date: May 31, 2019

(30) Foreign Application Priority Data

May 23, 2018 (KR) 30-2018-0023978

(51) LOC (12) Cl. 14-03

(52) U.S. Cl.

USPC ..... D14/138 G

(58) Field of Classification Search

USPC .. D14/138, 138 AA, 138 AD, 138 G, 203.1, D14/203.3, 203.5, 203.7, 248, 341, 496;

D21/329, 517

CPC . G06F 1/1626; H04M 1/0266; H04M 1/0202; H04M 1/026
